UNITED STATES PATENT OFFICE

JOHN H. MACARTNEY, OF SAN FRANCISCO, CALIFORNIA, ASSIGNOR, BY MESNE ASSIGNMENTS, TO TURBO-MILL COMPANY, LTD., A CORPORATION OF CALIFORNIA

METHOD OF GRINDING

Application filed December 15, 1930. Serial No. 502,282.

This invention relates to apparatus for and method of grinding, and is particularly adapted to the art of comminution, reduction, trituration and levigation, and includes apparatus and method adapted to reduction of loose and broken lumpy material, such as ores, cement, rock, clay and the like, to a required fineness of mesh.

Objects of the invention are to provide an apparatus wherein the bodies forming an agglomerate may be reduced or disintegrated by interimpaction of portions of the agglomerate with other portions thereof, while subjecting the agglomerate to the effect of centrifugal force; to provide a grinding apparatus wherein the attrition of agglomerate is accomplished without wear and tear on parts of the apparatus, and wherein the agglomerate is prevented from jamming; to provide for drawing of the triturated particles simultaneously with and separately from extruded particles of larger mesh; to provide means whereby the mesh of extruded particles may be varied; to provide a method of grinding or reducing agglomerate wherein attrition is accomplished in the presence of centrifugal force and simultaneously causing within the agglomerate a diametric movement radially relative to the direction of the centrifugal force.

This application relates to and is an improvement of the disclosure and subject matter of United States Letters Patent No. 1,441,162, in which I am joint inventor.

The present invention provides improvements of apparatus and method wherein finely triturated particles are simultaneously removed from the apparatus separately from the pulverized particles of larger mesh; to provide an apparatus and method wherein bodies of relatively oppositely rotated and relatively oscillated bodies of agglomerate are subjected to centrifugal force with the faces of the respective bodies in grinding contact and providing a continuous feed of new broken material while simultaneously and separately removing pulverized material of varying degrees of fineness.

With the above mentioned and other objects in view, the invention consists in the novel

construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more clearly comprehend the invention, reference is directed to the accompanying drawings, wherein

Fig. 1 is a vertical longitudinal transverse section on line 1—1 of Fig. 3.

Fig. 2 is a vertical lateral transverse section on line 2—2 of Fig. 1.

Fig. 3 is a vertical end view of the apparatus.

Referring to the drawings in which like characters of reference designate corresponding parts, 4 indicates, generally, a base frame of usual and well-known type and preferably which has a base 5 with vertical side walls 7 and end walls 8 with a top plate 9 which provide a chamber 10 within which operating mechanism may be conveniently arranged.

The frame may be bolted to a base or bed by any suitable means, such as spikes or bolts, through bosses 11 of the frame. The upper side of the top plate 9 is provided with tracks 12 at its opposite ends upon which carriages 13 are reciprocably slideable on runners 13^a, the carriages 13 being lockable at any position relative to the tracks by lock bolts 14 which slide with the carriage and have an end engaged within a slot 15 in the top plate.

The slideable adjustment of the carriages is accomplished by suitable reciprocation means, such as hand wheels 16 which have threaded shafts 17 engaging complementary threaded portions 18 of the carriages. Each carriage mounts upon suitable support 19 a housing 20 and within the housing is rotatably mounted a tubular shaft 21 which is provided with oppositely inclined conical roller bearings 22, and each of the shafts 21 mounts a pulley 23 keyed to the shaft by any suitable means, as by screw 24, and being rotatably actuated from any suitable power sources by

a belt (not shown) and preferably simultaneously in the same direction and at the same speed. A grinder drum indicated generally A is provided for receiving a continuous supply of agglomerate and progressively discharging same as it is triturated or pulverized. The respective shafts 21 mounts at their inner ends, to rotate therewith, truncated conical cup-like containers 25 preferably axially horizontally disposed, and having opposing relatively spaced open ends provided with peripheral flanges 26 upon which are removably mounted wearing shoes or plates 27, as by threaded bolts 28, the outer tapered wall of the containers being provided with helically arranged fins 29. Intermediate the opposing open spaced ends of the containers 25 is a central segment 30 of the drum A (best shown in Fig. 1), which is rotatable independently of the containers 25, being vertically supported on rotatable trunnions 31 which are grooved as at 32 to receive a circumferential runner 33^a which extends radially from the outer surface of segment 30. The segment 30 is preferably arcuate on its inner axially longitudinal face 33 and is provided at its circumferential edges with flanges 34 extended radially outward, said flanges mounting, by bolts 36, wearing shoes or plates 35, which are opposed to the shoes or plates 27 of the containers 25, and normally spaced a desired distance therefrom, as at 58, 59. The segment 30 is rotated oppositely and independently of the containers 25, and preferably at less revolutions per minute, and receives its rotation from the trunnions 31, one of which is keyed or otherwise fixedly secured to rotatable shaft 37 driven from a suitable power source by belt pulley 38, and preferably from the same power source which actuates the pulleys 23. A belt or chain 39 connects the second trunnion and thereby rotates same in the same direction as the driven trunnion; this form of drive being preferred since the second trunnion is rotatably mounted in a frame 40 which has one end pivotally mounted on shaft 37, as at 41, and has its other end 42 extending beyond the periphery of the second trunnion and thereat mounts a roller 43, which bears against a roller cam 44 which is mounted on and rotated by shaft 45 which is rotated from any suitable source, either independently or at a reduced speed ratio from the shaft 37. As is obvious, the rotation of cam roller 44 oscillates the frame end 42 vertically, which in turn vertically oscillates the central segment 30 of drum A, which is maintained in vertical alignment by rollers 46 which have grooves therein adapted to receive the runner 33^a. The rollers 46 have spring tension bearing against runner 33^a, and are mounted on a shaft 47 in a yoke 48 which has coil spring 49, the tension of which is regulated by manually operated hand

wheels 50 which operate threaded shafts 50^a mounted on guide members 51, which in turn are mounted at openings 52 in the arcuate portion of an inverted U-shaped frame 53 which foots on base frame 10, as at 54, and is secured thereto by bolts 55. The U-shaped frame extends arcuately over and is spaced from the outer wall of the drum A radial of the axis thereof.

Mounted on the frame 53, as by bolts 54^a, is housing 55^a which substantially encases the drum A and is provided with openings 56 in its side walls, and through which the rotatable shafts 21 extend. The housing 55^a has an inwardly extending circular ring plate 57, having a flange outward at one end mounted on the bolts 54 and a circumferential portion extending between the inner side of the U-shaped frame and the flanges 26 and 34, and having at its other end a radially inward flange which stops adjacent the outer wall of the segment 30 providing an opening 60, and thus substantially enclosing within housings the respective openings 58 and 59 through which pulverized agglomerate passes in the manner hereafter described.

The housings 55^a are provided, preferably at or near their bottom portions, with exhaust ducts or tubes 61 which lead to a proper bin or receptacle for the attritus.

Continuous feed means are provided, consisting of a hopper 62 into which agglomerate is received from a source of supply, not shown, and a feed tube 63, preferably stationary, extends from the bottom of the hopper through one of the tubular rotatable shafts 21, and having an end opening into one end of the drum A.

Disposed axially within the tube 63, and therebeyond through the hopper, is a helical spiral conveyer 64 which is mounted on and rotates with a shaft 65 which has suitable bearing in a wall of the hopper, as at 66, and may be further journaled in a support 67, and mounts suitable means, whereby said shaft may be rotated, such as pulley 68. The hopper and tube 63 are preferred to be removably mounted on the housing 20, as by bolts 69^a, so that the spiral conveyer may be inserted or removed for repair or replacement.

At the end of the drum A, opposite the feed end, is provided an exhaust tube 69 for minutely triturated material to the free end of which is attached a suitable suction tube 70. The tube 69 is preferably stationary and is mounted axially within and spaced from the inner walls of the rotatable tube 21, as at 74, by means of a plate 71 secured by bolts 72 to the outer end face of the housing 20. Within plate 71 are provided holes 73 through which air may pass inwardly to the drum through the space 74.

If desired, more rigidly and positively to direct the vertical oscillation of the end 42

of frame 40, said frame may be keyed, as at 75, in a slotted guideway in web 76, and said web may also act as a bearing for shaft 45.

Mode of operation.

Assuming a proper power source and belt, chain or other suitable and usual means of transferring power to the pulleys 23, 38 and 68, trunnions 31 and shaft 45, the shafts 21 10 are rigidly rotated, preferably from the same power source simultaneously in the same direction of rotation which may be either clockwise or counter-clockwise, thereby axially rotating the extreme drum section containers 25. Likewise the shaft 37 is rotated through pulley 68 and thereby rotates the trunnions 31 which support and thereby axially rotate the intermediate drum section 30, the rotation of which is in the opposite direction of 20 rotation relative to the sections 25, but preferably at a slower rate of rotation. It has been found satisfactory and efficient for practical purposes, if the extreme sections 25 be rotated approximately 1100 R. P. M. and the intermediate section 30 be rotated 600 R. P. M. though these ratios may be materially varied according to the material being ground, and the time in which it is desired to grind it. This rotation will cause the material B within 30 the sections 25 of the drum to be revolved in the same direction with those sections, and the material C to be revolved in counter-direction in the intermediate section 30, the faces B' and C' being maintained in contacted grinding relation by the centrifugal force set up by the said rotation, which is restrained by the peripheral walls of the drum.

Simultaneously with the rotation of the intermediate section 30, the shaft 45 is rotated 40 which actuates cam 44 and thereby oscillates end 42 of frame 40 which through trunnions 31 vertically oscillates intermediate section 30 of drum A with relation to the extreme sections 25, which oscillation continually 45 changes the contacting grinding faces of the agglomerate relative to each other, prevents jamming of the material and continually agitates the contacting agglomerate so that the triturated, decomposed or pulverized particles E of a desired mesh are enabled to work 50 through the mass of agglomerate and are thrown radially outward through the openings 58, 59 into a chamber within the housing 55 and is blown from said chamber through 55 outlet tube 61, by suitable blower means, such as fins 29, or by any suitable suction device operating from an outside source. The oscillation of the intermediate section 30 also distributes evenly the wear on plates 27 and 35. 60 The openings 58 and 59 may be regulated to various desired sizes of mesh by hand wheels 16 which have threaded engagement with carriages 13, which reciprocate the extreme sections 25 by means of shafts 21 mounted on the carriages.

In the course of the grinding operation, a mass of very fine particles F are formed of much smaller mesh than the particles E thrown out through the openings 58, 59 and it is of very considerable practical value to have these finer particles segregated from the larger particles exhausted from openings 61. Therefore, a suction means of any suitable type is connected to the tube 69 and these finer particles sucked from the axially central portion of the drum. To prevent any possibility of the suction through tube 69 from counteracting the centrifugal force of the revolved masses B and C or the suction of the exhaust tube 61, there is provided an air inlet at holes or ports 73 to the drum through the space 74 which opens adjacent the inner opening of tube 69.

It is preferred to have agglomerate continuously fed to the drum, which is accomplished by a continuous supply from a suitable source (not shown) in to the hopper 62, and thereafter propelled by the helical spiral 64 through the tube 63 and into the drum, preferably axially thereof, the newly fed material falling by gravity to the lower portion of the revolving agglomerate mass and being fed thereacross axially of the drum by the centrifugal force which is operative by reason of the revolving agglomerate, an angle of slippage D being maintained at approximately 30° to a perpendicular to the axis of the drum, the several bodies of agglomerate grinding on opposing contacting faces thereof with substantially no wear on the parts of the device.

What I claim and desire to secure by United States Letters Patent is:—

The method of grinding lumpy material which comprises the steps of subjecting two 105 masses of said material to the action of centrifugal force by revolving them in the same direction and interposing another mass of lumpy material intermediate the first mentioned masses and with faces in contact 110 therewith, restraining said material in such manner that each of said masses forms a separate continuous grinding surface, said masses being so placed that their grinding surface cooperate to grind the contacting material therebetween and subjecting said intermediate mass to centrifugal force by revolving same in the opposite direction to the first mentioned two masses.

In testimony whereof I have affixed my 120 signature.

JOHN H. MACARTNEY.
